HYDRAULIC TABLE RECIPROCATING MECHANISM

Wallace H. Wood, Worcester, Mass., assignor to
 Norton Company, Worcester, Mass., a corpora-
 tion of Massachusetts

Application May 26, 1938, Serial No. 210,213

6 Claims. (Cl. 121—45)

The invention relates to grinding machines, and more particularly to an hydraulically operated table reciprocating mechanism for a grinding machine.

5 One object of the invention is to provide a simple and thoroughly practical table reciprocating and reversing mechanism. Another object of the invention is to provide a table reversing mechanism with an improved hydraulically operated dwell control mechanism. Another object of the invention is to provide a table reversing mechanism with an hydraulically operated variable dwell control device whereby a variable dwell may be obtained at either or both 15 ends of the table reciprocation. A further object of the invention is to provide an hydraulically controlled dwell control for the table traversing mechanism. A further object of the invention is to provide an hydraulically operated table reciprocating mechanism with an hydraulically operated time delay control therefor to control the extent of dwell at each end of the table stroke. Other objects will be in part obvious or in part 20 pointed out hereinafter.

25 The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is an hydraulic diagram of the improved 35 table reciprocating mechanism and dwell control device therefor;

Fig. 2 is a cross sectional view through the table reciprocating mechanism, showing the actuating valve in cross section;

40 Fig. 3 is a longitudinal sectional view, on an enlarged scale, taken approximately on the line 3—3 of Fig. 2; and

Fig. 4 is a sectional view taken approximately on the line 4—4 of Fig. 3.

45 As illustrated in the drawings, a grinding machine embodying this invention may comprise a base 9 which supports a longitudinally reciprocable work table 10 on the usual V-way and flat way (not shown) for a longitudinal reciprocating movement relative to the base 9.

A fluid pressure operated reciprocating mechanism is provided to reciprocate the work table 10 comprising a fluid pressure cylinder 11 which is fixedly mounted on the under side of the table 10. The cylinder 11 contains a pair of spaced pistons

12 and 13 which are connected by a pair of hollow piston rods 14 and 15, respectively, with a pair of hollow brackets 16 and 17, respectively, which are fixedly mounted on opposite ends of the base 9.

In the preferred construction, the base 9 is formed with a box-like construction in which the lower portion thereof serves as a reservoir 20 for the fluid pressure system. Fluid is drawn from the reservoir through a pipe 21 by a motor driven fluid pressure pump 22 and is forced through a pipe 23 and a pipe or passage 24 to a table control valve 25. A fluid pressure relief valve 26 is provided in the pipe line 23 and is arranged to allow excess fluid under pressure to by-pass through a pipe 27 to the reservoir 20 in case the pressure within the hydraulic system increases above a desired predetermined pressure.

The control valve 25 is preferably of a balanced piston type reversing valve which includes a movable valve member 29 having formed integrally therewith a plurality of valve pistons 30, 31, 32, 33 and 34. Fluid under pressure from the pump 22 is forced through the pipe 23 and the pipe or passage 24 into a valve chamber 37 located between the valve pistons 31 and 32, and passes out through a pipe 39, into an aperture 40 in the bracket 16, to the hollow piston rod 14 and piston 12, into a cylinder chamber 41 to cause the cylinder 11 and table 10 to move in a direction toward the left (Fig. 1). During movement of the table 10 toward the left, fluid within a cylinder chamber 42 is exhausted through the piston 13, the hollow piston rod 15, and an aperture 43 within the bracket 17, and through a pipe 44 into a valve chamber 38 located between the valve pistons 32 and 33, and out through a pipe 45 which returns exhaust fluid through a pipe 46 into the reservoir 20.

A speed control valve 50, as illustrated in the drawings, is preferably formed integral with the valve 25. As illustrated diagrammatically in Fig. 1, the valve 50 is shown as a separate valve unit. The valve 50 is preferably located in the exhaust side of the fluid pressure system so as to maintain a uniform fluid pressure on the operative side of the main cylinder and thereby produce a more uniform table movement. This valve comprises a valve stem 51 which is provided with integrally formed valve pistons 52 and 53. The casing for the valve 50 is provided with a V-shaped port 54 which is located at one end of the pipe line or passage 45, conveying fluid from either the valve chamber 37 or 38, depending upon the position of the valve 25. The passage or outlet pipe 46 serves to exhaust fluid from a throttle valve 55

chamber 57, into the reservoir 20 within the base 9 of the machine.

The throttle valve 50 is arranged so that it may be moved longitudinally from a full line 5 position to a dotted line position. The valve is provided with an actuating knob 59 on the front end of the valve stem 51, which permits the valves to be rotated. In the preferred construction, the end of the valve piston 53, instead 10 of being a plane surface at right angles to the axis of the throttle valve, is arranged at an angle thereto. By providing an angularly positioned end face to the piston 53, any rotation of the valve member serves as a fine adjustment to cut off 15 more or less of the V-port precisely to regulate the exhaust of fluid from the system and thereby permit a fine regulation of the table speed.

In order that the piston 53 may be maintained in the desired adjusted position so as to enable 20 the table to be stopped and started as desired without changing the feed adjustment, a serrated or notched portion 60 is provided which is formed integral with the valve stem 51, and a spring pressed pawl 61 is carried by the valve 25 casing 50, so that when the knob 59 is rotated to adjust the valve piston 53 to give the desired table speed, the pawl 61 engages notches in the serrated portion 60 and serves to hold the valve piston in its adjusted position so as to permit 30 longitudinal and axial movement of the valve stem 51 by means of a control lever 70 to stop and start the table movement without upsetting the speed adjustment of the valve. The control lever 70 is pivotally mounted on a stud 71 which 35 is fixedly supported relative to the base 9 and serves to permit a rapid movement of the valve stem 51 to stop and start the table movement. The lever 70 is provided with an aperture 72 fitting loosely around a sleeve 73 which is mounted 40 on the valve stem 51. Trunnion pins 74 are provided on diametrically opposite sides of the aperture 72 on the lever 70 and are arranged to engage vertical slots 75 in the sleeve 72. It will be 45 readily apparent from the foregoing disclosure that when the throttle valve lever 70 is in the position indicated in full lines (Fig. 1), the valve stem is positioned so that the valve piston 53 uncovers all of or a portion of the V-port 54, allowing the table to move at a predetermined speed. 50 By moving the control into the position 70a, as indicated in broken lines in Fig. 1, the valve piston 53 is moved into position 53a, thereby closing the V-port 54 and stopping the table movement.

When the throttle valve is in a closed position 55 to stop the fluid pressure movement of the table 10, it is desirable to provide a suitable fluid bypass whereby the fluid may readily pass from the cylinder chamber 41 at one end of the cylinder 11 to the cylinder chamber 42 at the other end 60 thereof to facilitate a manual traverse of the table. In the preferred construction, a pipe or passage 80 is provided to connect the pipe 44 and the valve chamber 38 with a pipe or passage 81 provided as an extension of the pipe 39. When 65 the throttle valve 50 is in the closed position, as indicated in broken lines, fluid may readily pass from the cylinder chamber 41, through the pipe 39, the pipe 81, through a valve chamber 82 located between the valve pistons 52 and 53, 70 through the pipe 80, through the pipe 44, into the cylinder chamber 42. This by-pass in the throttle valve interconnects the cylinder chambers 41 and 42 so that when the fluid pressure system is shut off by closing the throttle valve 50, the table 10 75 may be readily traversed manually when desired.

A manually operative table traverse mechanism may be of the type shown in my prior United States Patent No. 2,071,677 and may consist of a manually operable hand wheel and a rack and gear mechanism for moving the table longitudinally.

A suitable reversing mechanism is provided to change the direction of movement of the table 11 as desired. In the preferred construction, the adjustable table dogs 90 and 91 are adjustably 10 mounted in a T-slot 92 formed in the front edge of the table 10. The dogs 90 and 91 are arranged to engage a stud 89 mounted on the upper end of a reverse control lever 93 which is pivotally mounted on the forward end of a rock shaft 94 15 which is rotatably supported in the base 9 of the machine. The lever 93 is operatively connected to move the valve stem 29.

In order that the table may be reversed with a minimum amount of vibration, it is desirable to 20 provide a lost motion connection between the reversing lever 93 and the reversing valve 25, so that during the initial movement of the reverse lever under the influence of the table dogs 90 and 91, the valve is not moved. This mechanism preferably comprises a short lever 95 which is fixedly keyed to the inner end of the rock shaft 94. A similar short lever 96 is rotatably mounted on the rock shaft 94 and is supported thereon by means of a bushing, so that the lever 96 is free 25 to oscillate relative to the shaft 94. The lever 96 carries a stud 97 which engages a groove 98 formed in an extended portion of the valve stem 29. The lever 95 is provided with an aperture 99. A pin 100 is fixedly mounted on the lever 96 and 30 projects within the aperture 99 in the lever 95. The lower ends of the lever 95 and 96 are provided with enlarged end portions 101 and 102, respectively, each of which is provided with a semi-cylindrical aperture 103 and 104, respectively. A spring 105 is provided within the semi-cylindrical apertures 103 and 104 and serves to hold the levers normally in a definite aligned 35 relationship to each other.

Assuming the parts of the reversing mechanism to be in the positions illustrated in Fig. 1, the table is moving in the direction toward the left, which movement continues until the reversing lever 93 is moved a sufficient distance in a counterclockwise direction to actuate the lever 40 95 through its lost motion movement until the aperture 99 engages the pin 100. This movement of the lever 95 relative to the lever 96 serves to compress the spring 105 and when the aperture 99 engages the pin 100, continued movement 45 of the table serves to throw the reversing valve stem 29 into a central or neutral position, as indicated in Fig. 3, in which position the pressures are balanced on opposite sides of the main cylinder 11. The compression of the spring 105 tends 50 to move the valve stem 29 toward the right (Fig. 3), which movement is prevented by means to be hereinafter described.

When the compression of the spring 105 is released, it serves to shift the valve from a central 55 or neutral position so as to uncover a port 111, decreasing the fluid pressure passing into a chamber 112 and increasing fluid under pressure passing into a valve chamber 113. It should be noted that the valve pistons 30 and 31 are of 60 different cross sectional area, and fluid under pressure entering the chamber 113 serves, through the differential piston area on the pistons 30 and 31 to move the valve stem 29 toward 65 the right, as viewed in Fig. 3, to move the valve 70 75 75

into its extreme reverse position and thereby cause a reversal in direction of movement of fluid under pressure to pass the same to the opposite end of the main driving cylinder 11 and thereby cause the table 10 to move in the opposite direction.

Due to the differential in piston areas between the pistons 30, 34 and 31, 33, respectively, the valve chambers 113 and 112 function as a pilot valve to cause a reversal of the reversing valve under the influence of fluid under pressure. The reverse lever 93 serves only to cause the reverse valve to move to a central or neutral position, as illustrated in Fig. 3, and the spring 105 then being under compression, serves to move the reverse valve slightly off center to change the respective openings of the ports 110 and 111 and cause fluid under pressure to operate through the valve chambers 112 and 113 to cause a fluid pressure reversal of the reversing valve, thereby combining the functions of a reversing valve and a pilot valve in a single valve unit and thereby eliminating the piping connections and losses due to passages between the various valves as experienced heretofore.

Fluid within the valve chamber 112 may exhaust through a port 120 and similarly, fluid within the valve chamber 113 may exhaust through a port 121, into reservoirs 122 and 123, respectively. When the valve piston 29 is moved to either end of its stroke, as shown in the diagrammatic illustration in Fig. 1, fluid within the chamber 113 is free to exhaust through port 121, a pipe 124, and through a pipe 125, into the reservoir 20. Similarly, when the valve stem 29 is moved toward the right, fluid within the valve chamber 112 may exhaust through the port 120, a pipe 126, and a pipe 127, into the reservoir 20.

In a cylindrical grinding machine, it is frequently desirable to provide a sufficient dwell of the table at the end of its reciprocatory stroke so that the work piece may rotate at least one complete rotation before the table stops its movement in one direction and starts its movement in the reverse direction. The period of dwell necessary to accomplish this result varies with the size of the work being ground, the width of the wheel being used, as well as the speed of work rotation and table reciprocation. It is, therefore, desirable to provide a variable dwell at either or both ends of the table stroke to accomplish the desired results. In the preferred construction, the dwell at the end of the table stroke may be accomplished by interrupting the reversal in movement of the control valve 25 and allowing it to dwell in a central or neutral position for a predetermined adjustable time interval.

In the preferred construction an hydraulically operated control mechanism is provided to control the delayed action of the reversing valve so that the table dwell at either or both ends of the table stroke may be varied as desired. This is preferably accomplished by providing a cut-off valve 130 between the pipes 124 and 125. The valve 130 is preferably a piston type valve, which is normally held in an open position by means of a spring 131, allowing free passage of fluid from the pipe 124, through a valve chamber 132, into the pipe 125. The valve 130 is arranged so that it may be automatically closed by introducing fluid under pressure into a cylinder chamber 133 which serves to raise the valve pistons 134 and 135 to close the port at the end of the pipe 124 and prevent passage of fluid therethrough. The

admission of fluid to the chamber 133 is preferably controlled by a control valve 135 which is preferably a piston type valve comprising a valve stem 136 having formed integrally therewith valve pistons 137 and 138. The valve stem 136 together with the valve pistons 137 and 138 are normally held in an uppermost position by means of a spring 139. The valve 135 is preferably actuated in timed relation with the movement of the table 10.

A bell crank lever 140 is pivotally mounted on a stud 141 on the base 9. A horizontally extending arm 142 of the bell crank 140 is arranged to engage the upper end of the valve stem 136. An upwardly extending arm 143 of the bell crank 140 is arranged in the path of an adjustable dog 144 which is adjustably secured to the under side of the table reversing dogs 90. When the table moves to the right, so that the dog 144 engages the arm 143 of the bell crank 140 and rocks it in a clockwise direction, thus causing a downward movement of the valve stem 136, it serves to open a port so that fluid under pressure may flow from the pipe 124, through a pipe 145, into a valve chamber 146 formed between the valve pistons 137 and 138, and out through a pipe 147, into the cylinder chamber 133, to move the valve pistons 134 and 135 upwardly against the compression of the spring 131, thus cutting off the flow of fluid between the pipes 124 and 125.

As soon as the dog 144 passes over the high point of the lever 143, the released compression of the spring 139 returns the valve stem 136 and the valve pistons 137 and 138 into the position shown in Fig. 1, thereby again cutting off the flow of fluid under pressure to the cylinder chamber 133. A pipe 150 controls the exhaust of fluid from the cylinder chamber 133. An adjustable needle valve 151 in the pipe line 150 serves to regulate the rate of exhaust of fluid therefrom and thereby regulates the time interval necessary for the valve pistons 134 and 135 to drop into the position shown in Fig. 1 so as to allow the passage of fluid from the pipe 124 into the pipe 125, and thereby permit the reversing valve stem 29 to shift under the influence of fluid under pressure into the reverse position, thereby changing the direction of movement of the table 10.

Similarly, a cut-off valve 160 of the piston type is provided which is normally held open by means of a spring 161 so that fluid passing through the pipe 126 may pass directly through a valve chamber 162, into the pipe 127, and return to the reservoir 20. The valve 160 comprises a pair of valve pistons 164 and 165 forming the valve chamber 162 therebetween. A control valve 165 is provided for controlling the admission of fluid under pressure to a cylinder chamber 163 so as to raise the pistons 164 and 165 to close the port at the end of the pipe 126 and thereby prevent the passage of fluid from the pipe 126 into the pipe 127. The valve 165 comprises a valve piston 166 having formed integrally therewith valve pistons 167 and 168. A spring 169 normally tends to hold the valve stem 166 together with the valve pistons 167 and 168 in an uppermost position (Fig. 1). In order that the valve may be opened in timed relation with the table movement, a bell crank lever 170 is pivotally mounted on a stud 171 which is fixedly supported on the base 9. A horizontally extending arm 172 of the bell crank 170 engages the valve piston 166. An upwardly extending arm 173 of the bell crank 170

- is arranged in the path of an adjustable dog member 174 adjustably supported on the under side of the table reversing dog 91. When the table 10 moves toward the left (Fig. 1), the dog 5 174 engages the arm 173 which serves to rock the bell crank 170 in a counterclockwise direction to cause a downward movement of the valve stem 166, thereby permitting fluid under pressure to pass from the pipe 24 through a pipe 175 and 10 a valve chamber 176 located between the valve pistons 167 and 168, into a pipe 177 which admits fluid under pressure to the cylinder chamber 153.
- The admission of fluid under pressure to the 15 cylinder chamber 163 causes an upward movement of the valve pistons 164 and 165 against the compression of the spring 161. As soon as the dog 174 rides over the end of the bell crank lever 173, the released compression of the spring 20 169 moves the valve stem 166 upwardly to block off the port at the end of the fluid pressure pipe 175 and thus prevent further passage of fluid to the cylinder chamber 163. The released compression of the spring 161 then tends to force 25 fluid from the cylinder chamber 163, through a pipe 180, into the reservoir 20. An adjustable needle valve 181 serves to throttle the exhaust of fluid from the chamber 163 and thereby serves to control the downward movement of the valve 30 pistons 164 and 165 and thus determines the time interval or period of dwell. When the valve pistons 164 and 165 have been moved downwardly into the position illustrated in Fig. 1, fluid under pressure may then pass from the pipe 126, through the valve chamber 162, and the pipe 127, which returns to the reservoir 20, thus allowing the reversing valve to be shifted into a reverse position under the influence of fluid under pressure.
- 40 The operation of this table reciprocating mechanism will be readily apparent from the foregoing disclosure. Assuming all of the parts of the machine to have been previously adjusted and the table 10 is traversed in the direction of 45 the arrow, namely toward the left (Fig. 1), this movement continues until the projection 190 of the table dog 91 engages the stud 89 on the reverse lever 93. Just before the projection 190 of the dog 91 engages the pin 89, on the reverse 50 lever 93, the dog 174 engages the arm 173 of the bell crank lever 170 and causes a downward movement of the valve stem 166 which serves to admit fluid under pressure to the cylinder chamber 163. This in turn causes an upward 55 movement of the pistons 164 and 165 to cut off the flow of fluid between the pipes 126 and 127. The reversing lever shifts the valve 25 to a central or neutral position, such as shown in Fig. 3, and at the same time compresses the spring 105 60 so that the spring tends to throw the valve slightly beyond a central position.
- The reversing lever throws the valve stem 29 to a central position in which position fluid passing through the pipe 24, as shown in Fig. 3, may 65 enter both the valve chambers 37 and 38 and pass through the ports 110 and 111, into valve chambers 112 and 113. The valve 130 being open, fluid entering the valve chamber 113 may pass through the pipe 124 and valve chamber 132 and the pipe 70 125 into the reservoir 20. Fluid entering the valve chamber 112 cannot pass out through the port 120 since the valve 140 is closed. The valve 29 remains in a central position until the valve pistons 164 and 165 move downwardly under the influence of the spring 161 as controlled by the 75

opening of the adjustable needle valve 181, thus holding the shifting of the reversing valve to a predetermined time interval before fluid under pressure may pass from the pipe 126 into the pipe 127 and return to the reservoir 20. As soon as the valve 160 opens, the released compression of the spring 105 serves to throw the valve pistons slightly beyond the central position and the fluid under pressure within the valve chamber 112, due to the differential piston areas of the 10 pistons 33 and 34, serves to complete the reversal of the valve so as to change the direction of flow of fluid within the system. The fluid under pressure from the pipe 24 then flows into the valve chamber 38 and through pipe 44 to the right-hand 15 cylinder chamber to cause the table 10 to move in a direction toward the right (Fig. 1).

Table 10 continues to move toward the right until the dog 144 engages the arm 143 of the bell crank 140 which serves to cause a downward 20 movement of the valve stem 136 to open the valve and admit fluid under pressure from the pipe 145, through the valve chamber 146 and the pipe 147, into a cylinder chamber 133 to cause an upward movement of the valve pistons 134 and 135 to 25 close the port at the end of the pipe 124 and prevent passage of fluid under pressure from the pipe 124 into the pipe 125. At the same time, a projection 191 of the dog 90 engages the pin 89 of the reverse lever 93 and starts it moving in a 30 clockwise direction to throw the reverse valve into a central or neutral position, and completion of the reversal of the valve 29 is accomplished in a manner similar to that above described at the other end of the table stroke.

By manipulation of the adjustable needle valves 151 and 181, the dwell at each end of the table movement may be adjusted as desired, that is, so that an equal dwell of the desired extent may be obtained at both ends of the table stroke or with no dwell at one end and a predetermined dwell at the other or a short dwell at one end and a comparatively long dwell at the other, depending upon the conditions and operation being performed by the machine.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as 55 illustrative and not in a limiting sense.

I claim:

1. In a grinding machine, a longitudinally reciprocable table, means including a fluid pressure piston and cylinder to reciprocate said table, means including a control valve to control the admission of fluid to said cylinder, a lever operatively connected to move said valve, adjustable dogs on said table to move said lever and shift the valve to a central or neutral position at the ends of the table stroke to stop the table movement, and a hydraulically controlled mechanism which is actuated in timed relation with the table movement at the end of its reciprocatory stroke to stop and hold the reversing valve in 70 a neutral position for a predetermined time interval before allowing the valve to shift into reverse position to start the table moving in the opposite direction.
2. In a grinding machine, a longitudinally re- 75

ciprocable table, means including a fluid pressure piston and cylinder to reciprocate said table, a reversing valve to control the admission of fluid to said cylinder, adjustable dogs on said table, to said cylinder, adjustable dogs on said table, means including a lever actuated by said dogs to shift the valve to a central or neutral position to stop the table movement, means including a pair of adjustable hydraulically controlled mechanisms each of which includes a table actuated valve which are actuated by the table movement at each end of its reciprocatory stroke to stop and prevent the shifting of said reversing valve into the reverse position and the starting of the table movement in the reverse direction until after independently adjustable time intervals at either end of the table stroke.

3. In a grinding machine, a longitudinally reciprocable table, means including a fluid pressure piston and cylinder to reciprocate said table, a reverse valve to control the admission of fluid to said cylinder, adjustable dogs on said table, means including a lever actuated by said dogs to shift said valve to a central or neutral position to stop the table movement, means including a hydraulically controlled fluid pressure mechanism operatively connected with the reversing valve to stop and hold said reversing valve in a central or neutral position, and a control valve actuated by the table at the end of its reciprocatory movement to actuate said hydraulically controlled fluid pressure mechanism so as to control the shifting of said valve and start the table moving in the reverse direction after a predetermined time interval.

4. In a grinding machine, a longitudinally reciprocable table, means including a fluid pressure piston and cylinder to reciprocate said table, a reverse valve to control the admission of fluid to said cylinder, adjustable dogs on said table, means including a lever actuated by said dogs to shift said valve to a central or neutral position to stop the table movement, a pair of independent hydraulically controlled fluid pressure mechanisms operatively connected with the reversing valve to stop and hold said valve in a central position when moved in opposite directions, and a pair of hydraulic valves which are actuated by the table at either end of its reciprocatory movement to actuate said independent hydraulically controlled fluid pressure mechanisms respectively so as to

control the shifting of said valve and start the table moving in the reverse direction after independently adjustable time intervals at either end of the table stroke.

5. In a grinding machine, a longitudinally reciprocable table, means including a piston and cylinder operatively connected to reciprocate said table, a control valve therefor which is arranged to admit fluid under pressure to either end of said cylinder, a pair of adjustable dogs on said table, a lever operatively connected to said valve and arranged to move said valve to a central or neutral position when acted upon by one of said dogs at the end of the reciprocatory movement of the table, a hydraulically controlled valve which is operatively connected to the control valve so as to prevent movement of said control valve beyond a central or neutral position, a valve actuated by said table dog to operate said hydraulically controlled valve, and a valve to control the rate of movement of said hydraulically controlled valve and thereby control completion of the reversal after a predetermined time interval.

6. In a grinding machine, a longitudinally reciprocable table, means including a piston and cylinder operatively connected to reciprocate said table, a reversing valve associated therewith and arranged to admit fluid under pressure to either end of said cylinder, a control lever operatively connected to move said valve, adjustable dogs on said table which are arranged to actuate said lever to shift the reversing valve to a central or neutral position at the ends of the reciprocatory movement of the table, a pair of hydraulically controlled valves to prevent shifting of the reversing valve beyond a central or neutral position, a pair of normally closed valves operatively connected with said hydraulically controlled valves respectively which are actuated by said dogs respectively to close said hydraulically controlled valves and thereby hold the reverse valve in a central or neutral position, and a manually adjustable throttle valve to regulate the exhaust of fluid from said hydraulically controlled valve which is arranged after a predetermined time interval to allow the reversing valve to shift into its reverse position after a predetermined period of dwell.

WALLACE H. WOOD. 50
